UNITED STATES PATENT OFFICE.

GEORGE B. POINDEXTER, OF SEATTLE, WASHINGTON, ASSIGNOR OF ONE-HALF TO
GEORGE E. MILLER, OF BREMERTON, WASHINGTON.

COMBINATION LOCK.

Application filed April 6, 1925, Serial No. 20,993. Renewed April 20, 1927.

This invention relates to improvements in combination locks, and more particularly to locks of that character adapted for use in automobiles as an ignition circuit switch 5 lock; the principal object of the invention being to provide a lock that is compact, strong and durable and operable only by one who is familiar with the combination.

Another object is to provide a lock that is 10 an improvement upon the lock disclosed by U. S. Patent No. 1,339,668 issued to me on May 11, 1920, in that it comprises fewer and easier assembled parts and a stronger assembly.

15 In accomplishing the various objects of the invention, I have provided the improved details of construction, the preferred forms of which are illustrated in the accompanying drawings, wherein—

20 Figure 1 is a side elevation of a lock embodied by the present invention, showing it mounted in a panel which may be the instrument board of an automobile.

25 Figure 2 is a front elevation of the same showing the combination dial.

Figure 3 is a central, longitudinal section of the lock with the stem and combination parts in locked position and the switch open.

30 Figure 4 is a similar view, showing the parts unlocked and the switch closed.

Figure 5 is a perspective view of the interior parts of the lock in disassembled relation.

Referring more in detail to the drawings—
35 1 designates a one piece lock casing, which is of cylindrical form, and provided near its forward end with an encircling flange 2 for receiving rivets 3, or the like, for the purpose of attaching the casing to a panel, wall or instrument board, as designated at 4. Fitted about the rearward portion of the casing is a housing 5 having an outturned flange 6 at its forward end adapted to seat within a recess 7 in the rear surface of flange 2 so as

40 to be held therein securely by the rivets 3 and panel 4. This housing extends substantially beyond the rear end of casing 1 and provides ample space for the switch contacts, presently described, and is closed by an end wall 8 having an aperture 9 through which the circuit wires 10 and 11 may enter the lock.

The lock casing is bored axially to provide forward and rearward compartments of different diameters; the rearward being the

greater and joins the other in an annular 55 rearwardly facing shoulder 12.

At the forward end of the lock casing is a circular opening 13 in which a dial plate 14 is rotatably fitted. This dial plate is fixed by screws 15 concentrically to a disk 16 that 60 seats upon an annular, inwardly facing shoulder 17 formed just within the opening 13.

Rotatably fitted within the casing just back of the disk 16 and held in spaced relation 65 therefrom by a split ring 18 fitted within the casing, is a freely rotatable disk 19. This disk has a pin 20 projecting through it, as is shown best in Figure 3, which is adapted to be engaged by a stud 21, fixed in the inner 70 face of the disk 16, when the latter disk is rotated to thereby effect rotation of the disk 19.

Likewise, spaced from the disk 19 by a ring 22, is a rotatable disk 23 that is provided in its forward side with a stud 24 adapted to be engaged by the rearward end of pin 20 so that rotation of the disk 23 may be effected by rotation of the dial plate 14, disk 16 and disk 19. The rear surface of disk 23 lies flush with the shoulder 12 and a disk 25 rests on this shoulder against the disk 23 to retain all the parts forwardly thereof in functional relation. The disk 25 is retained against rotation by means of a 80 lug 26 projecting from the shoulder 12 and which is adapted to seat within a notch 27, (see Figure 5) in the periphery of the disk and it is held against the shoulder by a sleeve 28 that is fitted on the casing and which is 85 held in place by an overlying plate 29 held by a spring 29' seated in an annular groove in the casing wall.

The disks 19, 23 and 25 are provided, respectively, with apertures 30—31 and 32 95 (see Figure 5) which are adapted, by rotative movement of the disks, to be brought into alinement and they are provided also centrally with openings 33 through which the lock stem 35 may extend for free rotative 100 and longitudinal shifting movement.

The stem 35 extends in the axial line of the lock and along its forward portion it is squared and it extends slidably through squared openings 36 in the dial plate and disk 16. At its forward end the stem has a knob 39 threaded thereon and fixed by a set screw 40 and by means of this knob, the stem

may be rotated or shifted longitudinally. When it is rotated, the dial plate and disk 16 rotate therewith but the disks 19, 23 and 25 are not rotated except through contact of the pin and studs fixed therein.

Fixed on the stem within the larger bore of the casing is a disk 42 from which a pin 43 extends forwardly and which is the same radial distance from the axial line of the stem as are the apertures 30, 31 and 32 in the disks 19, 23 and 25. The rearwardly directed portion of the stem is covered by an insulated sleeve 45 and at its extreme end has a head 46 of electrically conductive metal held in place by a nut 47.

Fitted within the rearward end of the casing 1 is a plate of fibre 48 or other nonconductive material, provided with an opening 49 through which the insulated end of the stem extends and fixed thereto by binding screws 50—51 are two spring metal contacts 52 and 53 which are connected respectively by the binding posts to the circuit wires 10 and 11 and are adapted to be engaged by the head 46 to close a circuit through the connection only when the stem has been pulled to its forward limit of travel. When the stem is at its inner position, as shown in Figure 3, no circuit is closed.

On the forward face of the dial are numbered markings and adjacent to the dial, on the casing, is a mark or arrow, as shown in Figure 2, by means of which the combination is determined.

Assuming that the various parts are so constructed and assembled, to lock the device, the stem is pushed inwardly to the position as shown in Figure 3 and is rotated several times so as to move the openings 30, 31 and 32 in the disks out of alinement so that the pin 43 or disk 42 cannot enter and the stem cannot be drawn forward.

To unlock the device it is necessary to know the combination which would consist of three separate readings and assuming that these are known, the operator rotates the knob in a certain direction through at least two complete revolutions before bringing the first number of the combination on the dial into registration with the arrow on the casing. By this rotative movement the stud 21 on the outer disk 16 is brought into contact with pin 20 in disk 19 which in turn contacts stud 24 on disk 23 to thereby rotate the latter disk to move the aperture 32 into registration with opening 33 in the fixed disk 25.

The stem is then rotated in the reverse direction to bring the second number of the combination into registration with the arrow and by this rotative movement the stud 21 is brought again into contact with pin 20 to rotate the disk 19 to a position at which the opening 30 will be alined with openings 31 and 32. Then by rotating the stem again

in a reverse direction to bring the third number of the combination into alinement with the arrow, the pin is alined with the three alined apertures 30, 31 and 32 and the stem may be pulled forwardly to thus bring the head 46 into contact with the contact arms to close the circuit.

It will be noted by reference to Figure 5, that the disks 19, 23 are provided with a plurality of apertures adjacent the central opening. These are provided in order that the studs on the disks may be moved to various places for the purpose of making various combinations. By releasing the screws 15 in the dial 14, this may also be adjusted to different positions to effect a change of combination.

Having thus described my invention, what I claim as new therein and desire to secure by Letters-Patent, is:

1. In a lock of the character described, a cylindrical casing, a dial rotatably fitted within one end of the casing, a non-rotatable disk fitted within the casing in spaced relation to the dial, a plurality of relatively rotatable disks fitted within the casing between the dial and non-rotatable disk, studs fixed to the dial and rotatable disks whereby rotative movement of the dial may be communicated to the rotatable disks; said rotative and fixed disks having eccentric openings adapted to be brought into alinement, a switch stem disposed co-axially of the casing to extend through the disks and dial and operable to rotate the dial, a plate fixed to the stem and a stud fixed to the plate normally retaining the stem against longitudinal movement except when said disk openings have been alined to receive the stud.

2. In a lock of the character described, a cylindrical casing provided interiorly with spaced apart annular seats, one of which is located adjacent the forward end of the casing, a dial plate rotatably fitted in the forward end of the casing against said shoulder, a disk seated non-rotatably on the other shoulder having an eccentric opening, a plurality of relatively rotatable disks disposed intermediate the said dial plate and the non-rotative disk provided with openings adapted to be brought into registration with each other and with the opening of the fixed plate, and a switch operating stem disposed to extend axially of the casing and through said dial and disks and operable to rotate the dial and disks to bring the said openings of the disks into and from alinement, a plate fixed to the stem back of the non-rotative disk and a stud on the said plate for retaining the stem against longitudinal movement except when said disk openings have been alined to receive said stud.

Signed at Seattle, King County, Washington, this 25th day of March, 1925.

GEORGE B. POINDEXTER.
